(57) **CLAIM**

We claim the ornamental design for a load control device, as
shown and described.

DESCRIPTION

FIG. 1 is a perspective view of a load control device according
to a first embodiment of our new design.

FIG. 2 is a front view thereof.

FIG. 3 is a left side view thereof.

FIG. 4 is a right side view thereof.

FIG. 5 is a top view thereof.

FIG. 6 is a bottom view thereof.

FIG. 7 is a perspective view of a load control device according
to a second embodiment of our new design.

FIG. 8 is a front view thereof.

FIG. 9 is a left side view thereof.

FIG. 10 is a right side view thereof.

FIG. 11 is a top view thereof; and,

FIG. 12 is a bottom view thereof.

The rear views form no part of the design and are omitted. The
portions of the drawings appearing in broken line are for
environment only and do not form a part of the claimed
design.
